US0D1094102S

(12) **United States Design Patent** (10) **Patent No.:** **US D1,094,102 S**
(45) **Date of Patent:** **** Sep. 23, 2025**

(54) **OIL JUG**

(71) Applicant: **Wilmar, LLC**, Kent, WA (US)

(72) Inventor: **Dezhi Zhang**, Shanghai (CN)

(73) Assignee: **Wilmar, LLC**, Kent, WA (US)

(**) Term: **15 Years**

(21) Appl. No.: **29/946,592**

(22) Filed: **Jun. 10, 2024**

(51) **LOC (15) Cl.** **09-01**

(52) **U.S. Cl.**

USPC **D9/527**; D9/524; D9/528; D9/533

(58) **Field of Classification Search**

USPC D9/527, 520, 523, 524, 533, 414, 417, D9/429, 432, 500, 516, 528, 530, 531,

D9/560, 566, 575; D23/211.1, 202

CPC B65D 1/00; B65D 1/02; B65D 1/0223; B65D 23/00; B65D 85/00

(57) **CLAIM**

The ornamental design for an oil jug as shown and described.

DESCRIPTION

FIG. 1 is a top/front perspective view of an oil jug embodying my new design;

FIG. 2 is a bottom/rear perspective view of the oil jug of FIG. 1;

FIG. 3 is a top view of the oil jug of FIG. 1;

FIG. 4 is a bottom view of the oil jug of FIG. 1;

FIG. 5 is a front view of the oil jug of FIG. 1;

FIG. 6 is a rear view of the oil jug of FIG. 1;

FIG. 7 is a left side view of the oil jug of FIG. 1; and,

FIG. 8 is a right side view of the oil jug of FIG. 1.

The broken lines show portions of the oil jug not claimed and form no part of the claimed design.

1 Claim, 6 Drawing Sheets
